ATTORNEY

UNITED STATES PATENT OFFICE.

DE WANE B. SMITH, OF DEERFIELD, NEW YORK.

DESIGN FOR A SPRAYER-BODY.

SPECIFICATION forming part of Design No. 29,624, dated November 8, 1898.

Application filed October 17, 1898. Serial No. 693,842. Term of patent 3½ years.

To all whom it may concern:

Be it known that I, DE WANE B. SMITH, a citizen of the United States, and a resident of Deerfield, in the county of Oneida and State of New York, have invented and produced a new and original Design for the Bodies of Sprayers, of which the following is a specification, reference being had to the accompanying drawings, forming a part thereof.

Figure 1 shows a perspective view of a body for sprayer of my design. Fig. 2 shows a side elevation. Fig. 3 shows another perspective from another point of view.

As shown in the drawings, the leading or material features of my design consist of the long cylindrical portion 1 and the short enlarged cylindrical portion 2, arranged at one

end of the cylinder 1 and converging therewith, the converging ends meeting and the diverging end of the part 2 being connected 20 with the part 1 by the connecting-piece 3.

Having described my invention, what I claim as new, and desire to secure by Letters Patent, is—

The design of a body for a sprayer, as herein shown and described. 25

In witness whereof I have hereunto subscribed my name, in the presence of two witnesses, this 7th day of October, 1898.

DE WANE B. SMITH.

Witnesses:

E. W. JONES,

SARAH A. BROWN.
